UNITED STATES PATENT OFFICE.

FIELDING SNEDIGAR, OF ELKADER, IOWA.

SNOW-PLOW.

SPECIFICATION forming part of Letters Patent No. 280,528, dated July 3, 1883.

Application filed October 17, 1882. (No model.)

To all whom it may concern:

Be it known that I, FIELDING SNEDIGAR, of Elkader, in the county of Clayton and State of Iowa, have invented a new and Improved 5 Snow-Plow, of which the following is a full, clear, and exact description.

The object of my invention to facilitate the removal of snow from railway-tracks.

The invention consists in a car provided 10 with a plow and with two long arms projecting from the front, to which arms transverse and vertical cutters are attached at the ends, whereby when the cutters are forced into a bank of snow they cut the bottom and sides 15 of a block of snow, upon which a hoe attached to arms pivoted to the car is dropped and cuts the end of the block of snow, which is withdrawn by backing the locomotive, and is then pushed to the sides of the track by the 20 plow as soon as the locomotive is moved forward.

Reference is to be had to the accompanying drawings, forming a part of this specification, in which similar letters of reference indicate 25 corresponding parts in all the figures.

Figure 1 is a longitudinal elevation of my improved snow-plow. Fig. 2 is a plan view of the same. Fig. 3 is a cross-sectional elevation of the same on the line *x x*, Fig. 2.

30 The plow A, which is provided with a double mold-board and an inclined central ridge or cutter, B, is attached to a box-car, C, which is coupled in front of the locomotive. Two long side bars, D, are pivoted to the side of 35 the small car C, and at the outer ends they are connected by a transverse horizontal cutter, E, which rests on the rails F, and is guided by clips I, attached to the under side of the cutter and resting against the sides of the rails. 40 Vertical cutters G, having their lower ends flared forward, are attached to the ends of the transverse cutter E. A cutter or hoe, H, is attached to the ends of two long arms or bars,

J, which are pivoted to the sides of the car and which are connected by a bail or cross piece, K, to which is attached a rope, L, passing over a pulley, M, on the cross-piece of two strong standards, N, on the car C. The lower end of the rope is attached to a windlass, which can be operated by hand or steam power.

The operation is as follows: The cutters and G are driven into the packed snow, the cutters cutting the sides and bottom of a block of snow. Then the hoe or cutter H is dropped and cuts the front end and sides of the block. If the engine is then backed, the hoe H draws out the block of snow, which is then drawn some place where it can be dumped at the side of the tracks. The hoe H is then raised, and then the engine is moved forward, upon which the plow A cuts into the block and throws it to the sides of the track. The engine continues to run forward and forces the cutters E into the bank of snow, the hoe H is dropped and another block is removed in the same manner as described above, and so on until the tracks are clear. In making curves the hoe must swing with the cutter-bars, so as to always drop in front of them.

Having thus described my invention, I claim as new and desire to secure by Letters Patent

In devices for removing snow from railway tracks, the combination of side and bottom cutters, G G E, adapted to run on the rails, a sequent drop-hoe, H, adapted to cut the front end and sides of the snow-block, and the double-mold-board plow A, having the central ridge or cutter, B, whereby the snow will first be cut at the bottom and sides, then cut off the sides and front end, and then thrown in two divisions, one to each side of the road as described.

FIELDING SNEDIGAR.
